UNITED STATES PATENT OFFICE.

EDMUND HOXIE, OF EVERETT, MASSACHUSETTS.

PNEUMATIC ECONOMIZER AND AIR-INJECTOR.

No. 823,278.

Specification of Letters Patent.

Patented June 12, 1906.

Application filed December 17, 1904. Serial No. 237,259.

To all whom it may concern:

Be it known that I, EDMUND HOXIE, a citizen of the United States, residing at Everett, in the county of Middlesex, State of Massachusetts, have invented a new and useful Pneumatic Economizer and Air-Injector, of which the following is a specification.

My invention relates to a novel construction of air-injectors and novel means of grouping and correlating the same.

It further consists in novel means of grouping nozzles of different lengths, whereby the longer nozzles may begin their work later than the shorter ones for the purpose of serving to accelerate the speed of the air already in motion.

It further consists of novel means for inducing atmospheric air for use in oil-furnaces, sand-blasts, forges, or for any purpose requiring less than the normal pressure of the plant to which it is attached and novel means of grouping the units in series or tandem.

It further consists of novel means of grouping or multiplying the nozzles within a single shell or casing.

It further consists in other novel features of construction, all as will be hereinafter set forth.

Figure 1 represents a plan view of a pneumatic economizer and injector embodying my invention. Fig. 2 represents a sectional view of Fig. 1. Fig. 3 represents a vertical sectional view of two of the units arranged in tandem and connected with a reducing-valve and their adjuncts.

Similar numerals of reference indicate corresponding parts in the figures.

Referring to the drawings, 1 designates the discharge end, mouth, or nozzle of a single-unit air-injector, which swells gradually toward the inlet end 2, a portion of which is cut away, as at 3, to form the atmospheric-air inlet or inlets, it being evident the number of these inlets may be increased as desired. To the end 2 of the casing is secured the head 4, adapted to receive the air-inlet tube 5, which is shown in the present instance as having threaded engagement with the head 4; but it is evident that equivalent means may be used to connect the same, or they may be made integral, if desired. The tube 5 is shown threaded internally at its end 6, thus enabling a hose or other supply-pipe to be readily attached thereto. The inner end of the tube 5

is closed or provided with a wall 7, extending through which are a plurality of ports 8,

which permit the motive fluid or pressure medium to enter the commingling-chamber 9 of the injector. The inlet-tube 5 is of such length that the discharge end will preferably terminate beyond the openings of the inlets 3 in order that the induction of air under atmospheric pressure through these inlets may be accomplished, the fluid under high pressure discharging through the ports or jets 8 into the commingling-chamber 9 of the injector. The discharge end or nozzle 1 may be threaded, or the threaded portion may be on an enlargement 10 thereof, as shown in Fig. 1, or equivalent means may be employed to adapt the injector to be readily connected with other units or to the connections leading to the forge or blast or other device.

In Fig. 3 two units 11 and 12 and a pressure-reducing valve 13 are shown arranged in tandem. The second or right-hand unit 12, besides having the opening 34 leading directly into it from the first unit 11, has a separate connection 14, which opens at one end into the tube 15, leading to the group of jets in said second unit 12, and at its other end receives its air-supply from the pressure-supply pipe 16. The inlet-port 17 of the second unit 12 has a check-valve 18, which is pivoted at 19 to the casing, which is shouldered, as at 20, and recessed so as to form a seat for the check-valve 18. This check-valve opens inwardly, and when the force of induction is sufficient to overcome the interior pressure tending to close the valve air under atmospheric pressure will be admitted to all of the units of the series. The reducing-valve 13 is located between the first unit 11 and the supply-pipe 21 and discharges through the pipe 16 into the pipe 14 and said first unit.

Another connection 22 leads from the valve 13 to the low-pressure receiver. Within the valve 13 is a piston-governed valve 23, adapted to actuate the controlling-valve 28, which is acted upon by the tension of the spring 24 and by the pressure from the low-pressure receiver, which normally tends to close the valve. The tension of the spring 24 may be varied by adjusting the screw or threaded stem 25, which has at its outer end the wheel 26 or finger-piece 26.

It will be apparent to those skilled in the art that in the construction seen in Figs. 1 and 2 the air, steam, or other fluid under pressure enters through the supply-pipe 5, thence through the group or series of ports 8 into the commingling-chamber 9 of the injec-

2
tor. By reason of the location of the discharge-ports 8 slightly in advance of the inlets 3 it will be apparent that the air under pressure escaping through the ports 8 causes 5 a supply of air to be drawn in through the inlets 3, which passes from the commingling-chamber 9 into the discharge-nozzle and is discharged from the latter in sufficient volume and pressure to operate the largest forge 10 or other devices which are in use.

In the construction seen in Fig. 3, where two or more of these units of the general character seen in Figs. 1 and 2 are placed in line or in tandem and the air is passed 15 through them consecutively, it will be apparent that each succeeding unit increases the density of the air until the desired point of density is attained, it being apparent that the incoming air flows through the pipe 21, 20 passing the valve 13, and thence through the pipe 16 to the pipe 29 and ports 30 and 30^x, which constitute the discharge of the first unit, into the commingling-chamber 31, into which additional air at atmospheric pressure 25 is drawn through the ports 32, which is commingled in the chamber 31. The commingled air then flows from the mouth 33, through the passage 34, into the commingling-chamber 35, thence to the mouth 36. In the 30 meantime a portion of the air passing through the pipe 16 is discharged through the pipe 14 into the pipe 15 and then through the ports 37, which constitute the discharge-nozzle for the second unit, into the commingling-chamber 35, it being apparent that the check-valve 18 will rise when the induction is sufficient to lift it and admit atmospheric air to the second unit 12. The discharge-nozzles or ports 37 in the second unit are shown as 35 being of the same length; but in those of the first unit the discharge-nozzles 30^x are shown as longer than the discharge-nozzles 30. The discharge-nozzles in any of the units may be made of uniform length or of different lengths, 40 as desired, and it is evident that the location of the longer discharge-nozzles in the end of the tube may also be varied. If a pressure-reducing valve is employed, the injector discharges first into a low-pressure receiver, and 45 the air is then passed on to the desired point of utilization.

When the consumption of air is less than the capacity of the device at full pressure, the pressure-reducing valve 13, which may 50 be of any approved type, will, by reason of the pressure and air coming from the low-pressure receiver through the pipe 22, tend to automatically close the controlling-valve 28, which prevents waste of compressed air, 55 whereby the same is used with great economy, as is evident.

I have found by practical experiments that less than one-sixth of the volume of air used in the forge or points of utilization comes 60 through the supply-tube 16, the rest being

the induced atmospheric air. A direct blast of highly-compressed air will always be below the freezing-point when rapidly expanded to nearly atmospheric pressure as it enters the fire; but this induced air so modifies the 70 extreme cold of the expanded air as to render it unnoticeable. In the direct blast from high pressure there is also a great loss of power expended in raising the pressure above the point required for use. The economy in 75 my device as compared with a direct blast is plainly evident. By arranging the units in series or tandem, as shown in Fig. 3, each succeeding unit taking the product of the preceding, air can be taken into a receiver or 80 used direct at a suitable pressure for use in oil-furnaces, sand-blasts, or for any purpose requiring less than the normal pressure of the plant to which they may be attached. Where a larger volume than can be supplied by a 85 single unit is needed, excellent results are obtained by grouping units of the same size side by side. The nozzles grouped in a single outer shell or frustum, as shown, or in different lengths in order that the longer nozzles 90 beginning their work later than the shorter ones, may serve to accelerate the speed of the air already in motion.

I have found that the elongated tubular form of the end of the casing of my injector 95 is an important aid in the introduction of atmospheric air.

It will of course be understood that the pipe 14 can be extended any desired length, depending upon the number of units employed, and is closed at the point with respect to the last unit.

In all the embodiments of my invention it will be apparent that various changes may be made in the precise manner of assembling 105 and connecting the various parts without departing from the spirit of my invention, and I do not, therefore, desire to be limited in every instance to the exact construction I have herein shown and described.

Having thus described my invention, what I claim as new, and desire to secure by Letters Patent, is—

1. An air-injector, comprising a plurality of units arranged in tandem, means for passing air under pressure successively from one unit to the next in series and each unit of said series having also an independent connection with the air-supply for increasing the speed of the air already in motion, and an inwardly-opening check-valve for the unit or units beyond the first unit.

2. An air-injector having its units arranged in series, each comprising a commingling-chamber and an elongated discharge-mouth 125 and having an inlet for air at atmospheric pressure, a supply-pipe discharging into the first unit, a discharge-nozzle for the second unit of less length than the discharge-nozzle for the first unit, a pipe leading from said 130

supply-pipe to the second unit and a check-valve for said second unit.

3. An air-injector having its units arranged in series, inlets for the induction of atmospheric air for each of said units, one of said inlets being provided with an inwardly-opening check-valve, and pipes for conveying air under pressure to said units, the discharge-nozzles of said pipes leading to said units being of different lengths and located slightly in advance of said inlets.

4. In an air-injector, a supply-pipe, a reducing-valve therein, a pipe adapted to lead motive fluid to said reducing valve for the purpose of actuating the latter, a controlling-valve actuated by said reducing-valve, a discharge-pipe leading from said controlling-valve, a unit having a commingling-chamber into which said discharge-pipe extends, a second unit into which said commingling-chamber discharges, a pipe leading from a point intermediate said valve and first unit to said second unit, and a commingling-chamber in the latter into which said pipe

discharges, the discharge-nozzles in said first unit being of greater length than the discharge-nozzles in said second unit.

5. In an air-injector, a supply-pipe, a reducing-valve therein, a pipe adapted to lead air or other fluid to said reducing-valve for the purpose of actuating the latter, a discharge-pipe leading from said valve, a unit having a commingling-chamber into which said discharge-pipe extends, a second unit into which said commingling-chamber discharges, a pipe leading from a point intermediate said valve and first unit to said second unit, a commingling-chamber in the latter into which said pipe discharges, a plurality of discharge-nozzles of different lengths in each unit, and a check-valve in said second unit said valve operating automatically to permit the ingress of atmospheric air.

EDMUND HOXIE.
